UNITED STATES PATENT OFFICE.

JOHN WOLF, OF CHICAGO, ILLINOIS, ASSIGNOR, BY MESNE ASSIGNMENTS, OF ONE-HALF TO LATHAM MACHINERY COMPANY, A CORPORATION OF ILLINOIS, AND ONE-HALF TO FREDERICK J. GREENE, OF RACINE, WISCONSIN.

STITCHING MACHINE.

Application filed December 27, 1926. Serial No. 157,120.

This invention relates to improvements in stitching machines.

The principal object of the present invention is to provide a simplified stitching machine in which the number of parts used to construct the machine are reduced to a minimum.

A further object of the invention is to provide a very efficient and inexpensive machine in which all of the parts are compactly arranged.

A still further object of the invention is to reduce the number of operative parts of a stitching machine to a minimum and thereby reduce the manufacturing cost and prolong the life of the machine.

These and other objects are accomplished by providing a construction and arrangement of the various parts in the manner hereinafter described and pointed out in the appended claims.

Referring to the drawings,

Fig. 1 is a front elevational view of my improved form of simplified stitching machine.

Fig. 2 is a cross sectional view of the same taken on the lines 2—2 in Fig. 1.

Fig. 3 is a cross sectional view taken on the lines 3—3 in Fig. 1.

Fig. 4 is a sectional view taken on the lines 30 4—4 in Fig. 3.

Fig. 5 is a detailed view showing a front elevation of the cutting mechanism.

Fig. 6 is a cross sectional view taken on the lines 6—6 in Fig. 1 showing the manner in which the pivoted bracket is mounted, and

Fig. 7 is a cross sectional view taken on the lines 7—7 in Fig. 5.

For the purpose of illustration I have shown my improved and simplified stitching machine detachably secured to an arm 10 of the main frame of the stitching machine. The stitcher head is removably secured to the arm 10 by means of three bolts 11 (only one of which is shown). These bolts 11 secure radially extending flanges 13 of the arm 10 to a plate 14. The plate 14 has secured thereto by means of screws 15 a spool supporting bracket 16 which is offset with respect to the longitudinal center of the machine and supports on the upper end thereof a spool of wire 17. The spool is held from accidental rotation by a pressed spring brake 18 which has its outer end curbed substantially in the form of a semi-circle 19 for guiding the wire through the usual wire straightener device 20

and wire spring pressed check mechanism 21. Rotatably mounted within the arm 10 in suitable bearings, not shown, is a main drive shaft 22, the outer end of which is provided with a driving pin 23 which is adapted to be seated in a recess 24 formed in a sleeve 25 of the spur gear 26 and butts against one end of a stud 27 as shown at 28. The stud 27 is journaled in a bearing portion 29 of the plate 14. The gear 26 is secured to the stud 27 by means of a pin 30. This arrangement permits the stud 27 to be substantially a continuation of the main drive shaft 22 and at the same time permits the stitcher head to be detached from the arm 10 when it is desired to remove the head. Secured to a reduced portion 31 of the stud 27 is a cam 32. Positioned forwardly of the cam 32 is a second cam 33 which has a wire feeding surface 34 on the outer periphery thereof. These cams 32 and 33 are secured to the stud in any well known manner, but preferably by a washer and bolt 35. Positioned directly above the cam 33 and operatively driven by a gear 35, which is secured to a stud 36, is a second feed cam or roller 37 which is provided with a peripherally projecting wire feeding projection or cam surface 38. The cam surface 38 extends almost completely around the feed roll as clearly shown in Fig. 1. This cam surface 38 co-operates with the feeding surface 34 of the cam 33 and impinges the wire therebetween for feeding the wire through the staple forming and driving mechanism. The stud 36 is mounted in a bearing portion 39 which is formed integrally with a pivoted bracket 40. The bracket 40 is pivoted by means of a shaft 41 to spaced bearing ears 42 formed integrally with the plate 14. The shaft 41 is secured in position by a set screw 43 in threaded engagement with the pivoted bracket 40 and engageable with the shaft 41. The free end of the pivoted bracket 40 is provided with a boss 44 having an aperture 45 extending therethrough which is adapted to loosely receive a threaded bolt 46. The lower end of the threaded bolt 46 is secured in a lug 47 formed integrally with the plate 14 by a pin 48 which extends through a registering aperture in the lug 47 and in the threaded bolt 46. The upper end of the bolt has in threaded engagement therewith a thumb screw 49 which may be adjusted on the bolt 46 for varying the tension on a compression spring 50 mounted on the bolt 46 between the thumb 105

screw 49 and the boss 44 of the swinging bracket 40. The bearing portion 39 of the pivoted bracket 40 extends through a relatively enlarged aperture 51 formed in the 5 plate 14. From the above description it will be noted that by reason of the pivoted bracket 40 and compression spring 50, which normally presses the pivoted bracket in a downward direction, that the feeding surface 38 of 10 the feed roll 37 is thereby resiliently pressed into engagement with the feeding surface 34 of the cam 33 when the wire is gripped between these feeding surfaces in the operation of feeding the wire. The feeding mechanism 15 may be adjusted to feed wires of varying lengths by adjusting the feed roll 37 in such a manner that the wire feeding surface 38 co-operates during a greater or less portion of the cycle of operation to impinge the wire 20 during a greater or less arcuate movement of each of these members. This is done by adjusting the roller 37 through the medium of a clamping washer and bolt 51'.

From the above description it will be noted 25 that by positioning one of the feed rollers or feed cams substantially on the main drive shaft I have eliminated a number of intermediate parts and have compactly arranged the feeding mechanism in close association 30 with the main drive shaft and thereby reduced the size of the machine to a considerable extent.

Formed in the front side of the plate 14 is a usual staple forming channel 51" having 35 reciprocally mounted therein a staple former 52 which in turn is provided with a vertically extending channel 53. The channel 53 of the staple former 52 has reciprocally mounted therein a staple driver 54. The staple former 52 is operably driven to form staples by the cam 32 which engages a roller 55 journalled on a pin 55' secured to the rear side and upper end of the staple former. The staple former is normally returned to its uppermost position by the compression spring 56 which is seated in a socket 57 formed in the 40 forward side of the plate 14 adjacent the staple former. The upper end of the compression spring 56 is positioned in a tubular member 58 which normally engages the pin 59 secured to the rear side of the staple former just below the roller 55. The tubular member is reciprocally mounted in the socket 57 as clearly shown in Fig. 2. The 45 staple driver 54 is operatively driven by the usual pitman connection 60 which has one end thereof connected, as shown at 61, eccentrically with respect to the axis of the cam 33 and the other end thereof connected, 50 as shown at 62, to the upper end of the driver. Co-operating with the staple forming and driving mechanism is the usual anvil 63 and staple supporter 64. The anvil 63 is provided with a wire groove 65 and a compression spring 66 which normally forces 55

the anvil out into the path of the staple forming and driving mechanism. The staple supporter is normally actuated into the path of the staple forming and driving mechanism by means of a compression spring 67. The 70 anvil 63 and the staple supporter mechanism 64, together with the staple forming and driving mechanism, co-operate in a manner well known in the art and a more detailed description of the operation and construction 75 of this mechanism is thought unnecessary.

Adjustably mounted adjacent the staple forming and driving mechanism is the improved wire cutting mechanism which comprises a horizontally adjustable block 68 80 which has a rearwardly projecting extension portion 69 which is adapted to slidably engage a channel 70 formed in the forward face of the plate 14 for horizontally adjusting the block 68 with respect to the forming and driving mechanism. Mounted in the block 68 and secured therein, in any well known manner, is the usual cutter tube 71. Secured to the block 68 at the opposite ends thereof and extending upwardly therefrom are two guiding pins 72. Reciprocally mounted on the 85 guiding pins 72 is a cutter block 73 and secured to the cutter block 73 on the side adjacent the staple forming and driving mechanism by means of a screw 74 is the usual knife 75. Formed on the inner side of and adjacent the top of the cutter block 73 is a 90 projecting flange 76 having thereunder an undercut channel 77. Intermeshing with the flange 76 and undercut channel 77 in a manner to engage and operatively actuate the cutter block 73 is a reciprocally mounted plate 78 which is positioned between the front plate 79 and the main plate 14 of the stitcher head. The front plate 79 is secured to the main 95 plate 14 by means of machine screws 79'. The front plate 79 is provided with an offset portion, as shown at 80, forming a shoulder 80' which forms a stop for the upward movement of the cutter block 73. The cutter block 73 together with its reciprocally mounted plate 78 is normally actuated to its uppermost position by a compression spring 100 105 110 115 120 125 130

81 which is seated in the recess socket 82 formed on the front side of the plate 14, as shown in Figs. 3 and 4. The upper end of the compression spring 81 is adapted to have seated thereon the head 82' of a spherical headed pin 83 secured to the rearside of the reciprocating plate 78 in any well known manner. The plate 14 is slotted, as shown at 83', so as to permit the spherical headed pin to reciprocate in the operation of severing the wire. The cutting mechanism is actuated to cut the wire by a lever 84 pivoted at 85 to the plate 14. The lever 84 has an upwardly curved portion, as shown at 86, which is adapted to be engaged by a cam portion 87 formed as an integral part of the wire feeding cam member 33. The lever 84 is fur-

ther provided with a laterally projecting portion 88 which is adapted to have, in threaded engagement therewith, an adjusting screw 89 and a lock nut 90. The lower end of the 5 adjusting screw 89 is adapted to engage the upper portion 91 of the reciprocally mounted plate 78. By this construction it will be readily seen that during each cycle of operation the cam surface 87 of the cam 33 will engage 10 the free end 86 of the lever 84 and swing said lever in a counter-clockwise direction, thereby forcing the reciprocating plate 78 downwardly with its cutter block 73 and actuating the knife to cut the wire extending through 15 the cutter tube 71. In connection with adjusting my improved cutter block horizontally with respect to the staple forming and driving mechanism I have provided a series of tapered or conical cavities 92 which are 20 adapted to be engaged by a tapered or conical point 93 of a thumb screw 94. The thumb screw 94 is in threaded engagement with the front plate 79, as shown at 95.

From the above description it will be readily 25 understood that when it is desired to adjust the cutter block 73 together with the cutter tube and block 68, the thumb screw 94 is unscrewed from engagement with one of the cavities 92 of the block 68 and the cutter 30 blocks 73 and 68 are horizontally adjusted by sliding this cutting mechanism in the channels or intermeshing parts 76 and 77 between the lower end of the reciprocating plate 78 in the upper part of the cutter block 73. 35 In this adjustment it will, of course, be understood that the cutter block 68 is adjusted longitudinally of the plate 14 by the rearwardly extending projection 69 engaging the channel 70 formed in the forward face of the plate 14, and when the predetermined adjustment 40 of the cutter block has been determined, the thumb screw 94 may be tightened to secure or clamp the cutter block in a relatively fixed position with respect to the staple forming and driving mechanism. 45

In the operation of the above described device it will be understood that the wire is fed from the spool 17 around the semi-circular guide 19 through the wire straightener and 50 wire checking devices 20 and 21 respectively, where it is engaged by the feeding surfaces 38 and 34 of the feed rollers and feed cams 37 and 33, respectively, through a circular guide tube 96 into the main tube 71 where it passes 55 into the groove 65 formed in the front end of the anvil 63. After the wire is thus fed the cam portion 87 of the wire feeding cam 33 engages the free end of the cam 86 and actuates the lever about its pivot 85, depressing the 60 cutting mechanism through the reciprocating plate 78 against the tension of the compression spring 81, thus causing the wire extending through the tube 71 to be severed adjacent the staple forming and driving mechanism. 65 Simultaneously with the severing of

the wire, the cam 32 engages the roller 55 journalled to the rear side of the staple former 52 and depresses the staple former 52 against the action of the compression spring 56. At the completion of the staple forming 70 operation the staple driver 54 is then actuated through the medium of the pitman connection 60 in driving the staple into the work beneath the head of the stitching machine. It will, of course, be understood that the anvil 63 is 75 forced from the path of the staple forming and driving mechanism by the staple driver which engages the bevelled front face of the anvil in its downward movement and then the staple supporting member 64 is likewise 80 forced outwardly by the downward movement of the staple driver as it is completing its work in driving the staples.

From the above description it will be readily seen that I have provided a very simple 85 and efficient wire stitching machine and one in which the parts are reduced to a minimum and at the same time I have retained a wide arrangement of adjustments.

It will be further noted that by mounting 90 one of the wire feeding cams of the feeding mechanism on the main drive shaft or an extension thereof that I have provided a construction in which all of the parts are compactly arranged and the number of parts reduced to a minimum, thereby reducing the manufacturing cost and also reducing the wear on the operative parts of the machine. 95

While in the above specification I have described one embodiment which my invention 100 may assume in practice, it will of course be understood that the same is capable of modification, and that modification may be made without departing from the spirit and scope of the invention as expressed in the following 105 claims.

The subject matter described and claimed in this application is disclosed in a joint application filed by John Wolf and Ernest Leschorn, Serial No. 737,230 filed Sept. 12, 110 1924, in which application the subject matter herein claimed was inadvertently set forth as being the joint invention of the said applicants, Wolf and Leschorn. This application may therefore be termed a continuation of the 115 joint application.

What I claim as my invention and desire to secure by Letters Patent is:

1. A wire stitcher comprising a head having a main former and driver operating shaft 120 rotatably supported therein, and a pair of connected feed rollers one of which is directly supported on the main shaft.

2. In a wire stitching machine, the combination with a frame, of a drive shaft mounted on said frame, a wire feeding mechanism directly connected with said drive shaft, and a staple forming and driving mechanism operatively connected with said drive shaft. 125

3. In a wire stitching machine, the combi- 130

nation with a frame, of a drive shaft mounted in said frame, a wire feeding cam secured to said drive shaft, and staple forming and driving mechanism operatively connected to said

5 drive shaft.

4. In a wire stitching machine, the combination with a frame, of a drive shaft mounted in said frame, a wire feeding mechanism mounted on said frame comprising a plurality

of feed rollers, one of said rollers positioned 10 concentrically with said drive shaft, and a staple forming and driving mechanism operatively connected with said drive shaft.

In testimony whereof I have signed my name to this specification, on this 24th day of 15 December, A. D. 1926.

JOHN WOLF.
